[57] **CLAIM**

The ornamental design for an extendible pedestal table, as shown and described.

DESCRIPTION

FIG. 1 is a perspective view of an extendible pedestal table showing my design;

FIG. 2 is a perspective view thereof with the movable panels in open position whereby to receive a panel insert;

FIG. 3 is a rear perspective view of the table of FIG. 2 with the panel insert removed; and

FIG. 4 is a perspective view of the table of FIG. 1 with the rotatable panels thereof being pivoted to an alternate position.

FIG. 1

FIG. 2

FIG. 3

FIG. 4
